GRINDING WHEEL DRESSING

Franklyn P. Hegeman, Union, N. J., assignor to
General Motors Corporation, Detroit, Mich., a
corporation of Delaware

Application March 13, 1941, Serial No. 383,197

16 Claims. (Cl. 125—11)

This invention relates to grinding wheel dressing and associated mechanism. An object of the invention is to provide improved mechanism for dressing the surface of a reciprocating grinding wheel. Another object is to provide improved wheel dressing mechanism wherein a dressing tool is fed towards the grinding wheel with increasing increments so that compensation will be obtained for the more rapid wear on the wheel as its diameter decreases in use. Another object is to provide means to control actuation of the dressing tool by the advance and retreat of a main slide on which the grinding wheel is constantly reciprocated.

To these ends and also to improve generally upon devices of this character, the invention consists in the various matters hereinafter described and claimed. In its broader aspects, the invention is not necessarily limited to the specific construction selected for illustrative purposes in the accompanying drawings in which

Fig. 1 is a front elevation with some parts in vertical section and with details of the work head and wheel dresser omitted.

Fig. 2 is a plan view, with some parts in section, of the wheel head and associated slides.

Fig. 3 is a right hand end view of Fig. 1 with some parts in section.

Fig. 4 is a cross sectional view of the two uppermost slides, some of the wheel head appearing in elevation.

Fig. 5 is a plan view of the wheel dressing mechanism.

Fig. 6 is a front view of Fig. 5, the hand wheel being removed.

Fig. 7 is an end view of the compensating mechanism.

Fig. 8 is an end view of the guide for the dresser slide.

Fig. 9 is a perspective view of details of the ratchet mechanism.

Fig. 10 is a perspective view of a portion of the cover for the slideway.

Referring to Figs. 1, 2 and 3, the machine comprises a main frame 10 on which is slidably mounted a lower or main slide 12 which is given one reciprocation at each cycle of grinding substantially as in Van Norman Patent 2,149,409. The left end of the machine may carry an oscillating head when grinding curved work or, by means of an adapter, the head can be fixed in an angularly adjusted position so that tapered work or straight cylindrical work may be ground. The machine will be described with special reference to the grinding of tapered raceways. At

5 the right end of the frame there are flat and V-ways to support corresponding ways on the main or lower slide 12 which is advanced or retracted by a reversible motor, the slide being advanced to get the grinding wheel inside the work and the slide being retracted at the end of the grinding operation.

10 A cross slide 14 sliding on ways 16 is adapted to be fed by a feed screw 18 which is actuated by ratchet mechanism similar to that of the patent. The cross slide has ways near its front to support an upper or grinding wheel slide 20 which is narrow and light and continuously reciprocated through a short stroke, the slide also supporting dressing mechanism which also normally partakes of the reciprocating movement. As appears best in Fig. 4, to guide the slide 20, a front slideway or guide bar 22 is fastened to the cross slide 14 by bolts while a rear slideway or 15 gib 24 is adjustably secured to the cross slide by bolts 26 passing through slots in the bar. The ways are V-shaped and a take-up is provided by screws 28 threaded in a lug on the cross slide and locked by a brass shoe which is backed up by a set screw. Oil conduits to conduct oil to the ways are provided and the ways are covered at the front by a dust shield 30 having an end flange which covers the end of the slideway. A similar dust shield 32 covers the rear slideway. 20 The upper slide 20 has at one end an upright portion or head 34 which is split at 36 and adapted to clamp a split eccentric bushing 38 in which the grinding spindle quill 40 is mounted, the bushing 38 being removable to permit the 25 mounting in the head of a larger size quill. The grinding wheel 42 has its spindle mounted for rotation in this quill and it is driven by a pulley 43 and a belt from a pulley not shown on a motor 30 adjustably mounted upon ways 46 on the top, 35 rear portion of the cross slide 14.

30 Referring particularly to Figs. 1, 2 and 3, the mechanism for giving continuous reciprocation to the upper slide 20 comprises a pair of lugs 48 35 projecting downwardly from the slide through a slot in the cross slide 14, the lugs supporting a pivot pin 50 on which are mounted a pair of tapered roller bearings 52 whose outer race rings are separated by a spacer. The inner race rings of the bearing are held on the pin 50 by a nut. The outer race rings are contained in an enlargement 54 of a link 56, the bearings being covered by cover plates 58. The other end of the link 50 also has a similar enlargement 60 closed by cover plates as indicated best in Fig. 3. In the enlargement are similar tapered bearings 62 whose inner

race rings are clamped upon a crank pin 64 projecting from a slide 66 adapted for movement of adjustment in ways formed across an enlargement 68 of a driven shaft 70. The slide 66 is adjustable to vary the throw of the crank pin 64 by means of an adjusting screw 72 threaded therein and held from endwise movement by a plate attached to the enlargement 68.

The shaft 70 is journaled for rotation in tapered roller bearings 74 contained in a housing 76 on a bracket 78 which is bolted to the cross slide 14. The bearings are covered by suitable caps containing seals. The shaft 70 is driven by a pulley 80 connected by a belt to a pulley 82 on an electric motor 84 which is fastened on a pivoted supporting plate 86. The plate has a boss 88 with a hinge pin which projects into rubber bushings carried by lugs 90 upon an upright bracket which is bolted on the cross slide 14 near the rear. The boss 88 has a downwardly extending arm 92 provided with an abutment screw 94 which is adjustable to vary the position of the motor and tighten the belt.

Referring particularly to Fig. 4, the upright portion of the upper slide 20 has a key 96 to locate a guide or housing 98 which is bolted on the upright part and has a cover 100 to form a rectangular guide for a slide 102 which pertains to the dressing of the grinding wheel. A gib plate 104 bears against the upper side of the slide and is backed up by cap screws. Where the slide projects through the ends of the housing, tight joints are formed by caps 106 having rectangular openings and provided with packings.

As shown best in Fig. 5, one end of the slide 102 is fastened by screws in a groove extending at an angle across the top of a bracket or nut 108 which is slit underneath and internally threaded to receive a feed screw 110 having a nib 112 which carries a dressing diamond 114 at the end. A ratchet wheel 116 is keyed to a reduced portion of the feed screw 110 and has a projecting hub 118 on which a pawl supporting arm 120 is loosely mounted for pivotal movement. The arm has a pivot stud 122 to pivotally mount a pawl 124 which is urged towards the ratchet wheel by a leaf spring 126. The pawl has a lifting pin 128 projecting laterally over the arm 120. The arm has extensions 130 adapted to abut, in various positions of advance, against a stop screw 132 adjustably fastened to a lug 133 on the cover 100, the arm being urged towards the stop screw by a coil spring 134, connected to a pin 136 on the arm 120 and to the bent end of an anchor pin 138 fastened to the bracket or nut 108. The screw 132 can be manually turned for adjustment by a knurled head 140 but the cross feed of the diamond is automatic and occurs whenever the slide 102 is retracted.

When the main slide 12 retreats, as at the end of a cycle, the slide 102 and the dressing mechanism are advanced, as will appear, carrying the pawl supporting arm 120 away from the stop screw 132, thereby allowing the coil spring 134 to swing the arm until a contact pin 144 on the extension 130 of the arm abuts against a tapered cam or stop plate 146 projecting from the bracket 108. Thus, during advance of the slide 102 and the ratchet mechanism, the pawl is drawn back to get a new grip on the ratchet wheel and, when the slide is subsequently retracted, the pawl supporting arm 120 engages the stop screw 132 and causes the pawl to feed the ratchet wheel and the feed screw and diamond. The amount of feed can be adjusted by screwing the stop screw 132

more or less into the lug 133 and clamping it with a screw. The tapered cam or stop plate 146 and the pin 144 provide means to automatically increase the advance of the diamond to compensate for increasing wear on the wheel as the latter decreases in diameter, it being evident that the feed screw 110 intermittently moves the ratchet mechanism towards the wheel and so advances the pin 144 along the tapered cam plate 146.

The following mechanism (best shown in Fig. 1) causes the advance of the slide 102 at the end of each grinding cycle. A clevis 150, fastened to the rear end of the slide 102, is pivotally connected to one end of an actuating rod or link 152, the other end of the actuating rod being pivotally connected to the upper end of an actuating lever 154 which is in the form of a bell crank. The lever is pivotally mounted on a headed pivot stud 156 threaded in a lug upon a bracket 158 which is fastened to the upper slide 20. The short arm of the bell crank carries a roller 158 adapted to ride along the enlarged rectangular head of a plunger 162 which is vertically slidable in bushings in a housing 164 which is fastened on the main or lower slide 12.

The upper bushing is held from rotation by a dowel pin 166 projecting into a slot of the housing 164 and the plunger is held from rotation in the bushing by a key pin projecting into a keyway. The lower end of the plunger carries a cam roll 168 adapted to ride on an inclined cam 170 fastened in a groove of a cam bracket 172 which is fastened on the main frame. When the main slide 102 is retracted to withdraw the grinding wheel from the work, the roller runs up the cam, lifting the plunger 162 and rocking the bell crank lever 154 to traverse the diamond along the grinding wheel.

When the main slide advances again, the plunger is compelled to descend by the action of a long coil spring 174 interposed between a pair of flanged abutment sleeves on a rod 176. One abutment sleeve engages a nut 178 threaded on the rod and the other engages a rounded surface on the lever 154, the rod 176 passing through a diverging slot in the lever and having a stop nut 178 fastened thereon and engaging a rounded surface on the other side of the lever. The rod 176 is threaded in a sleeve 180 which is flat at the sides to fit between ears on a forked stud 182 fastened to the housing 98 and having a pivot pin for the sleeve 180. The coil spring 174 will react upon the lever 154 and urge slide 102 towards retracted position with the pawl carrying arm 120 against the stop screw 132. This occurs whenever the main slide advances and results in moving the diamond back across the wheel and giving the diamond a feed movement to compensate for wear and reduction in diameter of the wheel.

When the main slide is advanced the grinding wheel reciprocates along the work piece W herein shown as internally tapered. The work is rotatably supported and driven in any suitable way as by a chuck or by rollers (not shown) mounted on a work head. Control of movable parts on the work head is effected by a forked cam 234 connected by a rod 236 and a coupling 238 to the main slide, the cam actuating a vertical plunger 240 in the axis of an oscillatable column 244. The plunger slides in a bushing in a plate 246 attached to a work head base 248 which is fastened on a swivel base 250. When grinding straight or tapered work, the swivel base is bolted

to an adapter 276 which has a circular groove 278 of T-shaped section to receive headed nuts 280 which are threaded on clamping bolts 282 passed up through a flange on the frame. The work head is thus capable of angular adjustment but it can be oscillated for use with curved work.

I claim:

1. In apparatus of the character indicated, a wheel slide having a grinding wheel, means for constantly reciprocating the wheel slide, a housing mounted on the wheel slide, a dressing slide shiftable in the housing but normally reciprocating with the wheel slide, a dressing tool on the dressing slide, a plunger, and a cam engaging the plunger for shifting the dressing slide with respect to the wheel slide to thereby traverse the dressing tool along the grinding wheel.

2. In apparatus of the character indicated, a main slide adapted for advancing and retreating movement, a wheel slide mounted on the main slide for reciprocation in the direction of said advancing and retreating movement and having a grinding wheel, means for constantly reciprocating the wheel slide with respect to the main slide, a dressing slide on the wheel slide and normally reciprocating therewith, a dressing tool on the dressing slide, and means for shifting the dressing slide with respect to the constantly reciprocating wheel slide to thereby traverse the dressing tool along the grinding wheel.

3. In apparatus of the character indicated, a main slide adapted for advancing and retreating movement, a wheel slide mounted on the main slide for independent reciprocation with respect to the latter and having a grinding wheel, means for constantly reciprocating the wheel slide with respect to the main slide, a dressing slide on the wheel slide and normally reciprocating therewith, a dressing tool on the dressing slide, and means responsive to a shifting movement of the main slide for causing the dressing slide to shift with respect to the constantly reciprocating wheel slide and thereby traverse the dressing tool along the grinding wheel.

4. In apparatus of the character indicated, a main slide adapted for advancing and retreating movement, a wheel slide mounted on the main slide and having a grinding wheel, means for reciprocating the wheel slide with respect to the main slide, a dressing slide on the wheel slide and normally reciprocating therewith, a dressing tool on the dressing slide, a plunger shiftable on the main slide, actuating means between the plunger and the dressing slide, and a relatively fixed cam for controlling shifting movement of the plunger in response to movement of the main slide.

5. In apparatus of the character indicated, a main slide adapted for advancing and retreating movement, a wheel slide mounted on the main slide and having a grinding wheel, means for reciprocating the wheel slide with respect to the main slide, a dressing slide on the wheel slide and normally reciprocating therewith, a dressing tool on the dressing slide, a plunger shiftable on the main slide, a pivoted lever having one arm riding on the plunger, actuating connections between the other arm of the lever and the dressing slide, and a fixed cam controlling the plunger.

6. In apparatus of the character indicated, a main slide adapted for advancing and retreating movement, a wheel slide mounted on the main slide and having a grinding wheel, means for reciprocating the wheel slide with respect to the

main slide, a dressing slide on the wheel slide and normally reciprocating therewith, a dressing tool on the dressing slide, a plunger shiftable on the main slide, a lever pivotally mounted on the wheel slide and reciprocable therewith, a rod connecting one arm of the lever to the dressing slide, the other arm of the lever riding on one end of the plunger, a spring urging said other arm against the plunger, and a cam at the other end of the plunger.

7. In apparatus of the character indicated, a main slide adapted for advancing and retreating movement, a wheel slide having a grinding wheel, means for reciprocating the wheel slide with respect to the main slide, a dressing slide on the wheel slide and normally reciprocating therewith, a dressing tool on the dressing slide, a plunger shiftable on the main slide, a cam to shift the plunger in response to movement of the main slide, means operably connected to the dresser slide and having a member in bearing engagement with the plunger, and one of the engaging parts being elongated to maintain contact with the other as the wheel slide shifts with respect to the main slide and the plunger.

8. In apparatus of the character indicated, a main slide adapted for advancing and retreating movement, a feed slide movable crosswise of the main slide, a wheel slide guided parallel to the main slide by the cross slide and having a grinding wheel, means for reciprocating the wheel slide, a dressing slide on the wheel slide, a dressing tool on the dressing slide, a plunger shiftable on the main slide, a fixed cam to shift the plunger in response to movement of the main slide, means connected to the dresser slide and having a member in bearing engagement with the plunger for transmitting movement of the plunger to the dressing slide, and said plunger having an enlarged head to maintain contact with the member as the cross slide and the wheel slide shift with respect to the main slide.

9. In apparatus of the character indicated, a wheel slide having a grinding wheel, means for reciprocating the wheel slide, a dressing slide mounted on the wheel slide and normally reciprocating therewith, a dressing tool having a feed screw supported by the dressing slide, means for shifting the dressing slide to cause the dressing tool to traverse the grinding wheel, and means for causing said shifting movement of the dressing slide to effect a turning of the feed screw.

10. In apparatus of the character indicated, a wheel head having a grinding wheel, a dressing slide shiftable with respect to the wheel head, a dressing tool mounted for feeding movement towards the grinding wheel, means for reciprocating the dressing slide to traverse the dressing tool along the grinding wheel, and means for causing one of the reciprocating strokes to feed said dressing tool towards the grinding wheel.

11. In apparatus of the character indicated, a wheel head having a grinding wheel, a dressing slide shiftable with respect to the wheel head, a dressing tool having a feed screw carried by the dressing slide, means for shifting the dressing slide to traverse the dressing tool along the grinding wheel, and means for causing said shifting movement to effect a turning of the feed screw.

12. In apparatus of the character indicated, a wheel head having a grinding wheel, a dressing slide shiftable with respect to the wheel head, a

dressing tool having a feed screw carried by the dressing slide, means for shifting the dressing slide to traverse the dressing tool along the grinding wheel, means for causing said shifting movement to effect a turning movement of the feed screw, and means for causing said turning movement to increase in amplitude when repeated.

13. In apparatus of the character indicated, a wheel head having a grinding wheel, a dressing slide shiftable with respect to the wheel head, a dressing tool having a feed screw carried by the dressing slide, means for shifting the dressing slide to traverse the dressing tool along the grinding wheel, and ratchet mechanism energized by said shifting movement for turning the feed screw.

14. In apparatus of the character indicated, a wheel head having a grinding wheel, a dressing slide shiftable with respect to the wheel head, a dressing tool having a feed screw carried by the dressing slide, a ratchet wheel on the feed screw, a feed pawl, a movable arm carrying the pawl, an abutment member on the wheel head, a spring for urging the arm towards the abutment member, and means for shifting the dressing slide with respect to the abutment member to cause the dressing tool to traverse the grinding wheel and to effect an actuation of the feed pawl.

15. In apparatus of the character indicated, a wheel head having a grinding wheel, a dressing slide shiftable with respect to the wheel head, a dressing tool mounted for feeding movement towards the grinding wheel, a member having an idle movement in one direction and a working movement in the other direction to effect a feed of the dressing tool, means for reciprocating the dressing slide to oscillate the member, and a tapered cam for controlling increase in the amplitude of successive oscillations of the member.

16. In apparatus of the character indicated, a wheel head having a grinding wheel, a dressing slide shiftable with respect to the wheel head, a feed nut carried by the slide, a dressing tool having a feed screw threaded in the nut, a ratchet wheel on the feed screw, a feed pawl, a movable arm carrying the pawl, an abutment member on the wheel head, a spring for urging the arm in a direction towards the abutment member, means for advancing the dressing slide to carry the arm away from the abutment, a cam in the path of the arm to control an idle movement of the arm during said advance, and means for retracting the dressing slide to cause said arm to engage the abutment and advance the pawl.

FRANKLYN P. HEGEMAN.
